X-RAY APPARATUS

Johan Marie Ledebœr and Antonius Wilhelmus Vingerhoets, Eindhoven, Netherlands, assignors, by mesne assignments, to Hartford National Bank and Trust Company, Hartford, Conn., as trustee

Application April 25, 1946, Serial No. 664,728
In the Netherlands November 10, 1942

Section 1, Public Law 690, August 8, 1946
Patent expires November 10, 1962

5 Claims. (Cl. 250—95)

1

It is generally desirable that if the voltage of an X-ray tube is altered the strength of the current passing through the tube should also be altered so that the load of the tube is maintained at a favourable value.

It is known to couple the member for the control of the current with that for the control of the tube voltage so that the current strength is automatically controlled by means of the voltage. In this case, the tube voltage is adjusted by means of a voltage selector which also controls the voltage of the primary of an auxiliary transformer whose secondary is included in the cathode heating circuit of the X-ray tube, the arrangement being such that an increase of the tube voltage results in a decrease of the filament heating current and thus of the current passing through the X-ray tube. Thus, it can be ensured that the tube is always loaded substantially with the maximum current strength that is admissible at the adjusted tube voltage.

The admissible maximum capacity of the tube depends on the loading period. With a shorter loading period a higher tube current is admissible than with a longer loading period. For this reason X-ray apparatus have been constructed in which the strength of the tube current is not only dependent upon the adjusted tube voltage but also on the loading period. In this case the control members of the tube current, the tube voltage and the loading period are so coupled together that the X-ray tube is continuously loaded with the maximum admissible power. Such X-ray apparatus are used in X-ray diagnosis; loading the X-ray tube with a power the tube is just capable of standing at the adjusted loading period ensures the advantage that the time necessary for taking photographic exposures, for example of moving parts of the human body, can be as short as possible. Such X-ray apparatus may be used with advantage for example for testing moving machine parts. Due to the tube current being automatically controlled in accordance with the tube voltage and the loading period the preparatory time for taking exposures is also shorter and the probability of errors being committed leading to a failure of the exposures is very slight.

If the tube voltage is to be kept constant continuously the strength of the tube current may also be caused to depend solely on the loading period.

In these known X-ray apparatus it has always been necessary to allow a certain play between the power automatically adjusted by the appa-

2

ratus and the limit of the really admissible capacity of the X-ray tube. According to the invention it has been found that in spite of the automatic coupling of the control members of the current strength with those of the tube voltage and/or loading period accidental load variations may occur. A few causes responsible to this may be indicated such as the generally inevitable variations of the supply voltage and the variations that may occur in the emissive power of the incandescent cathode of the X-ray tube.

The invention has for its object to obviate the said disadvantages of X-ray apparatus in which the member for controlling the tube current is coupled to the members for controlling the tube voltage and/or load duration and to increase the load capacity of the X-ray tube.

According to the invention, the apparatus comprises a device for maintaining the tube current substantially constant at the value adjusted by the said control members. Preferably, the member that controls the tube current in accordance with the tube voltage and/or the loading period is united with a device for keeping constant the tube current (with tube voltage and/or loading period originally adjusted) to form a single control device.

The control device may advantageously be formed by a variable impedance which is included in the heating circuit of the X-ray tube and whose value is dependent upon the adjustment of the members for controlling the tube current and/or the loading period as well as on the current passing through the X-ray tube. The control device may be formed by a choke coil having direct current pre-magnetisation. This choke coil may comprise a closed core having three columns. By arranging two windings on the two external limbs and including them in the heating circuit provision can be ensured that alternating current magnetisation does not occur in the central column. This column has arranged on it one or more control windings and the current passing through these windings is rendered dependent on the members for the control of the tube voltage and/or the loading period; in addition, the central column is provided with a winding which has passed through it a current whose magnitude is governed by the current passing through the X-ray tube.

In the apparatus according to the invention the value of the tube current is not only automatically controlled in accordance with the tube voltage and/or the load duration but with a given adjustment of the members for the control of the

tube voltage and/or the loading period the tube current is also automatically kept substantially constant so that accidental variations of the supply voltage or the emissive power of the incandescent cathode of the X-ray tube do not exercise any influence or only exercise a slight influence on the tube current and thus on the load of the X-ray tube. The invention permits of the value of the automatically adjusted capacity of the X-ray tube being chosen to be closer to the limit of the still admissible capacity than it used to be.

X-ray apparatus are known in which measures are taken to keep the strength of the discharge current passing through the X-ray tube substantially constant during the time of operation, the heating current being cut down at an increasing tube current. These measures are, however, not taken with X-ray apparatus in which the control of the tube current is effected by the members for controlling the tube voltage and/or loading period.

In order that the invention may be clearly understood and readily carried into effect it will now be described more fully with reference to the accompanying drawing, in which by way of example Figures 1 and 2 show the circuit diagrams of two embodiments of the invention.

The X-ray tube 1, which comprises an anode 2 and an incandescent cathode 3, is connected with the interposition of a rectifier valve 4 to a terminal of the secondary 5 of a high-voltage transformer 6. The incandescent cathode 3, which is supplied from the heating current transformer 7, is connected to earth at 8. The discharge current passes through a milliammeter 9 and then through a resistance 10 which has one end connected to the other terminal of the transformer winding 5 and to a terminal of the condenser 11. The other terminal of the condenser is connected to the anode of the X-ray tube. When the X-ray tube is in use it has passing through it pulsating direct current which is smoothed by the condenser. This current sets up a potential difference between the ends of the rheostat 10.

The primary 12 of the high-voltage transformer 6 is connected with the interposition of a voltage selector 13 to an autotransformer 14 which for part of its winding receives the voltage via connecting terminals 15-16 for the supply voltage. By means of the voltage selector 13 the primary voltage of the high-voltage transformer is controlled while at the same time the winding 17 which is arranged on the central column of a choke coil 18 is connected with the interposition of a rectifier 29 to the voltage selector 13. The two outer limbs of the core have arranged on them a winding which is formed by two parts 19-20 and is connected in series with the primary of the heating-current transformer 7. The operation of the choke coil relies on influencing the permeability of the iron core through the direct current pre-magnetisation. The higher the direct current that sets up the pre-magnetisation, the smaller is the permeability so that the inductive resistance of the alternating current winding 19-20 decreases. The pre-magnetisation is due to the current in the winding 21 which is supplied by the battery 22. The control of the current strength passing through the X-ray tube is automatically effected with the aid of the voltage selector 13 by means of which the voltage at the winding 17 on the choke coil is adjusted. The connection must be such that if higher operating voltages for the X-ray tube are chosen the current in the winding 17 sets up a magnetic field

which is oppositely directed to the field of the winding 21 so that an increase of the current strength results in a decrease of the direct current pre-magnetisation of the choke coil. Due to this the inductive resistance of the alternating current winding increases so that the heating current of the tube decreases. Connecting the voltage selector to the lower tube voltages has the opposite effect and increases the current passing through the X-ray tube. The source of voltage 22 has part of the resistance 10 connected in series with it. The potential difference at the resistance 10 brought about by the discharge current passing through the X-ray tube is oppositely directed to the voltage brought about by the battery current so that an increase of the current passing in the tube results in a decrease of the direct current that passes through the magnetisation winding 21. This decrease in current results in a reduction of the pre-magnetisation so that the inductivity of the choke coil increases and thus the resistance of the alternating current winding. This results in a decrease of the heating current of the X-ray tube so that the current in the X-ray tube is also reduced. This has the effect of the tube current being automatically stabilised at a value capable of being adjusted by means of the movable contact 23 on the resistance 10 and which is so chosen in connection with the load characteristic curve of the X-ray tube used that at a given voltage at the tube the optimum current strength occurs. A different adjustment of this contact will generally be required on the tube being replaced with another.

Referring to Figure 2, the core of the choke coil is shown to be provided with a number of windings. The pre-magnetisation of the core is effected by means of a separate winding 23 which is connected to the terminals 24-25 of a source of direct current. A variable resistance 26 connected in series with the winding serves for the adjustment of the current strength in the tube in accordance with the value corresponding, according to the nomogram, to a given voltage. The pre-magnetisation is influenced by the current in the winding 17 which is obtained through a rectifying device 29 from part of the winding of the series-connected transformer 14 and is adjusted by the voltage selector 13 simultaneously with the tube voltage. This device permits of the X-ray tube being constantly quite automatically operated with the full load. For this purpose the control choke coil has arranged on it a further winding 30 having passing through it direct current which is adjusted as a function of the loading period. For this purpose a time-switch device is shown to comprise a three-electrode valve 31 whose grid is connected to an R. C.-circuit 32-33. The adjustment of the time period is effected by the choice of the cathode potential by means of a potentiometer 34 which is connected to a source of direct voltage 35 in parallel with the R. C.-circuit. Simultaneously with the adjustment of the cathode voltage the current in the winding 30 is also controlled. The X-ray tube and the devices associated therewith by means of which the voltage supplied by the transformer 6 is rectified are not shown in the drawing. The winding 5 has passing through it alternating current which is proportional to the current passing through the X-ray tube. By obtaining current from the resistance 27 which upon rectification by the system 28 passes through the winding 21 on the iron core 18 of the choke coil the direct current pre-

magnetisation varies in accordance with the tube current variations.

By a proper choice of the various currents the direct current pre-magnetisation can be influenced in such sense that at any adjustment of the control members the tube is loaded to the limit of its capacity and the tube current remains constant with this adjustment irrespective of other influences.

What we claim is:

1. A control circuit for an X-ray tube comprising a low tension circuit for energising the cathode of the tube including an iron core variable reactor for controlling the energisation of the cathode, a separate high tension circuit for applying a potential to the anode of the tube including means to select a potential of desired value and means to derive a unidirectional potential proportional to the selected potential, means to derive a potential proportional to the current flowing through the tube, and means to premagnetize the core of said reactor, said variable reactor comprising a first winding coupled to said means for deriving a unidirectional potential proportional to the applied potential for varying the reactance thereof in accordance with the applied potential and a second winding connected to the means for deriving a potential proportional to the current flowing through the tube for varying the reactance thereof in accordance with the current flowing through the tube.

2. A control circuit for an X-ray tube comprising a low tension circuit for energising the cathode of the tube including an iron core variable reactor for controlling the energisation of the cathode, a separate high tension circuit for applying a potential to the anode of the tube including means to select a potential of desired value and means to derive a unidirectional potential proportional to the selected potential, means to derive a unidirectional potential proportional to the current flowing through the tube, and means to premagnetize the core of said reactor, said variable reactor comprising a first winding coupled to said means for deriving a unidirectional potential proportional to the applied potential for varying the reactance thereof in accordance with the applied potential and a second winding magnetically opposed to the first winding and connected to the means for deriving a potential proportional to the current flowing through the tube for varying the reactance thereof in accordance with the current flowing through the tube.

3. A control circuit for an X-ray tube comprising a low tension circuit for energising the cathode of the tube including an iron core variable reactor for controlling the energisation of the cathode, a separate high tension circuit for applying a potential to the anode of the tube including means to select a potential of desired value and means to derive a unidirectional potential proportional to the selected potential, means to derive a unidirectional potential proportional to the current flowing through the tube, means to derive a unidirectional potential proportional to the loading time of the tube, and means to premagnetize the core of said reactor, said variable reactor comprising a first winding coupled to said means for deriving a unidirectional potential proportional to the applied potential for varying the reactance thereof in accordance with the applied potential, a second winding connected to the means for deriving a potential proportional to the current flowing

through the tube for varying the reactance thereof in accordance with the current flowing through the tube, and a third winding connected to the means for deriving a potential proportional to the loading time of the tube for varying the reactance thereof in accordance with the loading time.

4. A control circuit for an X-ray tube comprising a low tension circuit for energising the cathode of the tube including an iron core variable reactor for controlling the energisation of the cathode, a separate high tension circuit for applying a potential to the anode of the tube including means to select a potential of desired value and means to derive a unidirectional potential proportional to the selected potential, and means to derive a unidirectional potential proportional to the current flowing through the tube including a source of direct current potential for premagnetizing the core of said reactor, said variable reactor comprising a first winding coupled to said means for deriving a unidirectional potential proportional to the applied potential for varying the reactance thereof in accordance with the applied potential, and a second winding magnetically opposed to the first winding and connected to the means for deriving a potential proportional to the current flowing through the tube for varying the reactance thereof in accordance with the current flowing through the tube.

5. A control circuit for an X-ray tube comprising a low tension circuit for energising the cathode of the tube including an iron core variable reactor for controlling the energisation of the cathode, a separate high tension circuit for applying a potential to the anode of the tube including means to select a potential of desired value and means to derive a unidirectional potential proportional to the selected potential, means to derive a unidirectional potential proportional to the current flowing through the tube, means to derive a unidirectional potential proportional to the adjusted loading time of the tube, and means to premagnetize the core of said reactor, said variable reactor comprising a first winding coupled to said means for deriving a unidirectional potential proportional to the applied potential for varying the reactance thereof in accordance with the applied potential, a second winding connected to the means for deriving a potential proportional to the current flowing through the tube for varying the reactance thereof in accordance with the current flowing through the tube, and a third winding connected to the means to derive a unidirectional potential proportional to the loading time for varying the reactance thereof in accordance with the loading time, said first, second and third windings being disposed on the central leg of a shell-type core of the reactor.
